UNITED STATES PATENT OFFICE

2,178,362

TRANSFER OF TOTALS FOR CASH
REGISTERS

William H. Robertson, Dayton, Ohio, assignor to
The National Cash Register Company, Dayton,
Ohio, a corporation of Maryland

Original application March 4, 1927, Serial No.
172,660. Divided and this application April 13,
1932, Serial No. 604,890

8 Claims. (Cl. 235—6)

This invention relates to repeat mechanism for cash registers and the like, but more particularly to repeat mechanism for the type of machine shown and described in the co-pending application for United States Letters Patent, Serial Number 172,660, filed March 4, 1927, by William H. Robertson, which issued into Patent No. 1,924,-
290 on August 29, 1933, of which this application is a division.

One object of this invention is to provide a machine having a plurality of totalizers with means for transferring a total from one totalizer to another subsequently to the totalizing operation and without knowledge that such total is to be transferred. Another object is to provide means whereby a total may be reentered in the totalizer from which it was taken after said totalizer has been returned to zero.

With these and incidental objects in view, the invention consists of certain novel features of construction and combinations of parts, the essential elements of which are set forth in appended claims and a preferred form of embodiment of which is hereinafter described with reference to the drawings which accompany and form part of this specification.

Of said drawings:

Fig. 1 is a perspective view of the machine.

Fig. 2 is a vertical cross sectional view showing one of the amount banks and its associated mechanism.

Fig. 3 is a detail view showing the total control lever and its associated mechanism, together with the motor bar and the mechanism for releasing the machine.

Fig. 4 is a detail view of the cam for engaging and disengaging the totalizer with the actuators during adding operations.

Fig. 5 is a detail view showing the cam for engaging and disengaging the totalizer with the actuators during read operations.

Fig. 6 is a detail view of the totalizer differential operating mechanism.

Fig. 7 is a detail view of the repeat release key together with its interlocks and associated mechanisms.

Fig. 8 is a perspective view of the interlock between the repeat release key and the various other mechanisms of the machine.

Fig. 9 is a top-plan view of the totalizer shift-

ing mechanism together with the main cam shaft.

Fig. 10 is a front elevation of the totalizer selecting mechanism.

Fig. 11 is a detail view of a part of the totalizer selecting mechanism.

GENERAL DESCRIPTION

The machine in which the present invention is embodied is provided with four banks of amount keys and one bank of transaction keys. The instant machine is also provided with a plurality of totalizers, each of which may be selected by a lever situated at the front of the machine. A manipulative member commonly called a total lever is provided for controlling the various functions of the totalizers. The instant machine is provided with both electrical and manual means of operation, and may be released for either electrical or manual operation by means of a starting bar conveniently located on the keyboard.

A repeat release key is also provided in the instant machine for use when it is desired to duplicate preceding transactions. The repeat release key may also be used for transferring amounts from one totalizer to another and for re-entering totals in a totalizer which had been cleared by the preceding operation.

In the following description the above mechanism pertinent to the instant invention will be described in detail:

DETAILED DESCRIPTION

Amount banks

The machine of the instant invention is provided with four banks of amount keys 50 (Figs. 1 and 2) slidably mounted in key frames 51 supported on rods 52 and 53 carried in the side frames 54 and 55 (Figs. 2, 7 and 9). Each key 50 is held in its outer or normal position by a coil spring 56 (Fig. 2). Each bank is provided with a flexible detent 57 which cooperates with a stud 58 secured in each key 50. The depression of a key shifts the detent 57 downwardly against the tension of a spring 59 until the stud 58 passes the shoulder on the detent 57 whereupon the spring 59 shifts the detent upwardly to hold the key in its depressed position.

Each key bank is also provided with a lock-

40

45

ing bar 60 (Fig. 2) which upon release of the machine is moved upwardly by mechanism to be hereinafter described, thereby moving said locking bar 60 beneath the studs 58 of the undepressed keys and over the stud 58 of the depressed key, thus locking the undepressed keys in their outer positions and the depressed key in its inner position. The flexible detent 57 and the locking bar 60 are slidably mounted on two studs 61 (Fig. 2) secured to the key frame 51.

Each bank of amount keys is provided with a zero stop pawl 62 (Fig. 2) for controlling the differential mechanism, to be later described, when no key is depressed in the bank. The pawl 62 is rocked to its ineffective position by a stud 63 carried by the detent 57 when any key is depressed in the associated amount banks. Depression of a key lowers the detent 57 as above described, thereby rocking the zero stop pawl 62 clockwise by engagement of the stud 63 with the shoulder 64 on the zero stop pawl 62. The zero stop pawl is pivoted on a stud 65 (Fig. 2) on the key frame 51 and held in engagement with the stud 63 at all times by a spring 66.

25   Transaction bank

The transaction bank of keys 69 (Fig. 1) is of the same construction as the amount banks. These keys are used for printing identification 30 characters and indicating the kind of transaction entered in the machine.

Operating mechanism

After the operator has depressed the desired 35 key representing the transaction, he may operate the machine either by means of a crank 75 (Fig. 1) or by an electric motor (not shown). The motor is located beneath the registering mechanism and access thereto may be had through a door 74 in the front of the cabinet. Depression 40 of the motor bar 76 releases the clutch mechanism and closes the circuit through the motor. Such mechanism is shown and described in United States Letters Patent to Kettering and Chryst No. 1,144,418 dated June 29, 1915.

45   The machine is operated by means of a main cam shaft 80 (Figs. 3 and 9) which receives one complete revolution for each machine operation. Rotation of the cam shaft 80 is effected by a train 50 of mechanism including pinion 81, pinions 82 and 83 secured together and mounted on a stud 84, and pinion 85 secured to worm gear 86 which meshes with a worm gear 87 on the main cam shaft 80. The pinion 81 is secured by a sleeve to 55 one member of the motor clutch mechanism above referred to. The motor clutch is driven by a pinion (not shown) on the motor armature which meshes with a gear secured to a bevel pinion (neither of which is here shown). The bevel 60 pinion meshes with a bevel gear 91 (Fig. 3) secured to one member of the motor clutch mechanism. When the motor is released the clutch drives the pinion 81 and through the train of pinions and gears 82, 83, 85, 86 and 87, causes the 65 main cam shaft 80 to receive one complete rotation.

When the machine is operated by the crank 75 (Fig. 1) the main cam shaft 80 is given one complete rotation by means of a train of gears, not 70 here shown, but fully illustrated and described in the parent application above referred to.

Machine releasing mechanism

The machine is released for operation by depression of the motor bar 76 (Fig. 3). The motor

bar 76 is removably mounted on a plate 116 slidably mounted on the right frame 55 and normally retained in its upward position by a spring 117. The plate 116 carries a stud 115 adapted to cooperate with a pivotally mounted pawl 114. Depression of the motor bar 76 withdraws the pawl 114 from beneath a flange 113 on a slidably mounted link 110 and permits a spring (not shown) to lower the link 110. Downward movement of the link 110 rocks an arm 104 outwardly 10 (Fig. 3) to withdraw said arm from the path of the driven member of the clutch mechanism, thereby permitting the machine to begin an operation.

This release of the clutch mechanism also closes 15 a circuit through the electric motor, causing it to operate. The mechanism for closing the circuit through the motor is well known in the art and is illustrated and described in the above mentioned Kettering and Chryst patent.

20   The link 110 is restored to its normal position upward near the end of the operation of the machine, and the arm 104 rocks into the path of the clutch mechanism, thereby stopping the machine by mechanism not here shown but fully illustrated and described in the above referred to parent application.

The well known non-repeat pawl 122 (Fig. 3) is provided for preventing a second operation of the machine in case the motor bar 76 is not permitted 30 to return to its normal position before the end of the operation of the machine. If the operator should hold the motor bar in its depressed position as the machine completes its operation, the non-repeat pawl 122 moves beneath the flange 35 113 under tension of a spring 123, which normally holds the pawl 122 engaged with a flange 124 of the release pawl 114. The operation of this non-repeat mechanism is well known in the art and it is felt that further description is unnecessary.

40   Locking bar operating means

As above mentioned, each bank of keys is provided with one of the locking bars 60 (Fig. 2) which is rocked beneath the stud 58 of the undepressed amount keys and above the studs 58 of the depressed amount keys, thereby preventing depression of a key or the release of a depressed key after the machine has been released for 45 operation.

Mechanism for operating this locking bar is 50 under control of the link 110. The link 110 (Fig. 3) has secured thereto a stud 155 embraced by a bifurcated arm 159 of a yoke 157 (see also Fig. 8) extending between the side frames 54 and 55. 55 Each locking bar 60 is provided with a stud 158 (Fig. 2) which projects into a bifurcated arm 159 loosely mounted on a shaft 160 carried by the side frames. The downward movement of the link 110 upon releasing the machine, as above described, rocks the yoke 157 clockwise to engage and rock the arm 159 counterclockwise, which by means of the stud 158 raises all the locking bars 60 into locking position.

The yoke 157 (Fig. 8) is provided with an arm 65 163 (Figs. 7 and 8) for preventing operation of a repeat release key 164 after the machine has been released. The repeat release key is mounted on a rod 215 supported in the side frames 54 and 55. The repeat release key and its associated mechanism will be described hereinafter.

Restoration of the link 110 to home position near the end of machine operation, as hereinbefore described, returns the yoke 157 to its normal position thereby permitting the locking bars 60 75

and arms 159 to be returned to their normal positions by a spring 168 (Fig. 2). However, if for some reason the above parts should not be restored by the springs 168 the key releasing mechanism to be presently described, positively restores the locking bars and the arms 159 to their home or normal positions.

Key release mechanism

Mechanism has been provided for automatically releasing the depressed amount and transaction keys at the end of machine operation. Near the end of machine operation the shaft 160 (Fig. 2) is rocked clockwise by mechanism not here shown, but fully illustrated and described in the parent application referred to hereinbefore. This causes an arm 171 secured to the shaft 160 to lower the flexible detent 57 thereby disengaging the hook on said flexible detent from the stud 58 in the depressed amount key 50, whereupon the depressed amount key 50 is returned to home position by its spring 56. Clockwise rocking of the shaft 160 also causes the arms 171 to engage a stud 185 in the arms 159 to positively return the locking bars 60 to their normal ineffective positions.

Manual means have also been provided for rocking the shaft 160 clockwise to release the depressed amount and transaction keys. Such manual releasing mechanism is not here shown, but reference may be had to the parent application for a full description thereof.

Differential mechanism

The differential mechanism for all the amount banks is identical. Therefore the differential mechanism for one amount bank only will be described herein. The differential actuator is adjusted under the influence of a spring, the differential movement thereof being controlled by the lower end of the depressed amount key.

Referring to Fig. 2, a shaft 215 journaled in the frames 54 and 55 has pivoted thereon an actuator 216 provided with teeth 217 and a forwardly extending arm 218. A spring 220 is tensioned to rock the actuator 216 in a clockwise direction, but is prevented from doing so by a Universal rod 221 (Figs. 2 and 6) carried by a pair of arms 222, only one of which is shown (Fig. 6), secured to the shaft 215. One of these arms (Fig. 6) is adjacent the left side frame 54 and the other arm 222 is located adjacent the right side frame 55. Secured to the left-hand arm 222 (Fig. 6) is a disk 223 having gear teeth which mesh with a segment 224 pivoted on a stud 225 carried by the left frame 54. The segment 224 has mounted thereon a pair of rollers 226 which cooperate with a pair of cam plates 227 secured to the main cam shaft 80.

When the cam shaft 80 rotates during the machine operation the segment 224 rocks the arms 222 and the rod 221 first in a clockwise direction (Fig. 6) thereby permitting the actuator 216 (Fig. 2) to be rocked under the influence of the spring 220 until stopped by the end of the depressed key 50, unless prevented from moving by the zero stop pawl 62 (Fig. 2). The rod 221 advances far enough to permit nine steps of movement of the actuator 216.

After the actuator 216 has been positioned under control of one of the keys 50 and the rod 221 has finished its clockwise movement a totalizer pinion 230 (Fig. 2) is moved into mesh therewith in a manner to be hereinafter described. After the totalizer pinion has been engaged with the

actuator 216 the segment 224 (Fig. 6) is rocked counterclockwise by the cams 227 thereby moving the rod 221 back to its normal position to carry the actuators 216 back to home position. This backward movement of the actuator 216 adds an amount on the totalizer pinion commensurate with the value of the amount key depressed. 5

A stop is provided to prevent overthrow of the arms 222 and the Universal rod 221 (Fig. 6). The arm 222 which is adjacent the left frame 54 is provided with surfaces 231 and 233 which engage a stud 232 when said arm 222 is rocked to its extreme positions. Thus the stud 232 limits the movement of the arm 222 and the rod 221 in both directions. 15

Transaction bank differential mechanism

An actuator 216 is also provided for the transaction bank, but this actuator is only used for adjusting the type carriers and indicators in a manner to be later described. There is no totalizer pinion 230 associated with the transaction bank. 20

Totalizers

The machine of the instant invention is provided with two interspersed totalizers, each consisting of a set of pinions 230 (Fig. 9). A mechanism to be presently described, is provided for shifting the two sets of pinions 230 into operative alignment with the actuators 216. The totalizer pinions 230, rotatably mounted upon a sleeve 259 (Figs. 2, 9 and 10) are properly spaced thereon by collars 270. The sleeve 259 is slidably mounted on a shaft 260 supported by two arms 261 to a shaft 262 journaled in the frames 54 and 55. 35

Secured to the shaft 262 is an arm 263 (Figs. 3 and 9) having pivoted thereto a link 264. The link 264 carries a stud 736 adapted to cooperate with a bifurcated arm 729 pivoted to the frame 55. The arm 729 has a cam slot 728 through which projects a stud 727 fast in the total lever 162. As the total lever is moved to the "Add" position the stud 727 cooperating with the cam slot 728 rocks the arm 729 causing a stud 265 in the link 264 to engage a notch 266 (see also Fig. 4) in an arm 267 during adding operations. The arm 267 (Fig. 4) is provided with a roller 268 which projects into a cam slot in a cam disk 269. The cam slot in the disk 269 is so timed that during the operation of the machine the totalizer pinions 230 are engaged and disengaged from the actuators 216 at the proper time. 45

Alining devices, including an arm 275 and an aliner 276 (Fig. 2) are provided for maintaining the totalizer pinions in proper alinement when disengaged from the actuators 216. These parts are so arranged that the aliner becomes disengaged at the time the totalizer pinions begin to engage the actuator 216, and becomes re-engaged just before the totalizer pinions are entirely disengaged from the actuators, all of which is fully explained in the parent application above referred to. 55

Alining means is also provided for holding the totalizer pinions 230 of the totalizer which is not in operative alinement with the actuators 216 against rotation. This means consists of a bar 286 (Figs. 2 and 9) slotted to permit free rotation of the pinions of the totalizer in operative alinement with the actuator 216. 65

Transfer mechanism

A transfer mechanism has been provided for the totalizers for carrying "1" to the next higher order pinion when the lower order pinion passes 75

from "9" to "0". It is felt that a description of the above transfer mechanism is unnecessary herein, as reference may be had to the Robertson application, Serial Number 172,660, of which the present application is a division, for a full description of the transfer mechanism.

Totalizer selecting means

Means have been provided for selectively shifting the pinions of the desired totalizer into operative alignment with the actuators 216 and such means will now be explained. The sleeve 259 (Figs. 9 and 10), which as before stated, carries the two sets of totalizer pinions 230, is shifted by a manually operable lever 319 (Figs. 1, 3, 9 and 10). The righthand end of the sleeve 259 has secured thereto a collar 320 (Figs. 9, 10 and 11) engaged by an upwardly extending arm 321 of a totalizer selecting slide 322 slidably mounted on a crossbar 281 supported between the frames 54 and 55. The slide 322 is provided with a rack 323 (Fig. 11) which meshes with a pinion 324 secured to a shaft 325, the forward end of which is journaled in the bar 281 and the rearward end in the back frame 241. Secured to the shaft 325 is an arm 326 (Figs. 3 and 9) having forwardly extending flanges 327, adapted to be pivoted to rearwardly extending flanges 328 on the lever 319 to form a connection between the lever 319 and the shaft 325.

The lever 319 has a finger 330 (Figs. 3 and 10) adapted to cooperate with notches 331 in a plate 332 secured to the crossbar 281. The lower end of the lever 319 is adapted to cooperate with a flange 336 of an arm 338 secured to an arm 334 by a hub loosely mounted on a stud 335 secured in the frame 55. A spring 333 (Fig. 3) is tensioned to rock the arms 334 and 338 clockwise.

When it is desired to select the totalizer, the upper end of the lever 319 (Figs. 3 and 10) is first pressed rearwardly against the tension of the spring 333 until the finger 330 is withdrawn from the notch 331. This frees the lever 319 so that it may be rocked either to the right or to the left, as the case may be. Rocking of the lever 319 through the shaft 325, (Fig. 11) pinion 324 and rack 323, shifts the totalizer selecting slide 322 to move the desired totalizer into position to be engaged with the actuators. The selected totalizer is retained in alignment with the actuators by means of aligning notches 340 (Fig. 9) in the slide 322 being engaged by aligning teeth 341 on the arm 283 when the latter is rocked to engage the totalizer with the actuators.

An interlock is provided between the lever 319 and the machine releasing mechanism which prevents release of the machine when the lever 319 is out of effective position, and locks the lever 319 in effective position after the machine has been released. Pressing the lever 319 rearwardly, preparatory to shifting the totalizer, rocks the arm 334 (Fig. 3) counterclockwise until its upper end is in the path of a stud 342 in the link 110. This prevents releasing of the machine by holding the link 110 in ineffective position until the lever 319 is moved into an effective position. Likewise releasing of the machine for an operation lowers the link 110, causing the stud 342 to move into the path of the arm 334 to lock the lever 319 in effective position during machine operation.

Indicators

Calling attention to Figs. 1 and 2, the machine is provided with a series of indicators 420, one for each amount bank and one for the trans-

action bank. These indicators are first restored to zero and then set up according to the amount of differential movement given the totalizer actuators 216 during machine operation.

For each indicator there is a segment 421 (Fig. 2) loosely mounted on the shaft 215, and meshing with a gear 422. One of the gears 422 is secured to the end of a shaft 423 and one is secured to each of the sleeves 424. Each gear 422 meshes with a gear 425 loosely mounted on a rod 426 carried by the side frames 54 and 55. The gears 425 mesh with pinions 427 secured to the indicators 420. When the rod 221 (Fig. 2) moves forwardly to allow setting of the actuators 216, it contacts a surface 429 on the segment 421 and moves said segment far enough clockwise to return the indicators 420 to their zero positions. The gears 425 are stopped in zero positions by a rod 430, which passes through slots cut in said gears 425 and acts as a positive zero stop for the indicators 420.

A coupling pinion 440 (Figs. 2 and 7) is provided for each differential mechanism for coupling the actuators 216 with the segments 421. The coupling pinion 440 is normally in mesh with the actuators 216 and the segments 421, but at the beginning of the machine operation said pinions are moved out of mesh long enough to permit the actuators 215 to be adjusted under control of the depressed amount keys 50 and also for permitting the rod 221 to restore the segments 421 to zero, as above described. After the actuators 216 have been adjusted the coupling pinions 440 are again moved into mesh and the actuators are returned to their home positions. Such movements of the actuators is transmitted to the indicators 420 by the segments 421 and the train of gears above described. Thus the indicators are set commensurate with the value of the amount keys depressed.

The coupling pinions 440 (Fig. 2) are all loosely mounted on a rod 441 (see also Fig. 7) carried by two arms 442 secured to a shaft 443 journaled in the frames 54 and 55. Also secured to the shaft 443 is an arm 444 carrying a stud 445 embraced by a notch in a link 446 guided at its upper end by a stud 447 which projects into a slot in the repeat release key 164. The lower end of the link 446 is pivoted to an arm 448 secured to the shaft 210. Secured to the shaft 210 is an arm 449 (Fig. 3) provided with a roller 450 projecting into a cam groove 451 on one side of a cam 452 secured to the main cam shaft 80.

At the beginning of an operation of the machine the cam 451 through the arm 449 rocks the shaft 210 clockwise to lower the arm 448 (Fig. 7) and the link 446. The lowering of the link 446 rocks the arm 444 and shaft 443 counterclockwise to disengage the coupling pinions 440 from the actuators 216 and the segments 421. After the actuators 216 have been positioned according to the depressed amount keys and all the segments 421 have been moved to zero, the cam groove 451 through the mechanism actuated thereby moves the coupling pinions back into mesh with the actuators and segments. The rod 221 then returns the actuators to their home positions to adjust the indicators as above described.

From the above description it is apparent that at the end of the operation of the machine the indicators and the trains of mechanisms connected thereto remain set according to the previous operation. However, the actuators 216 are all

returned to home positions and remain thus when the machine is idle.

Secured to the back frame 241 is an aligner 468 (Fig. 2) adapted to cooperate with the tooth spaces of the coupling pinions 440 when said coupling pinions are disengaged from their actuators 216 and the segments 421. This retains the pinions 440 in proper alignment with said actuators 216 and segments 421 so that upon subsequent re-engagement they will mesh properly with each other.

Type carriers

As hereinbefore mentioned the shaft 423 (Fig. 2) and each sleeve 424 has secured on their left-hand ends gears 422, which are adjusted according to the differential movement of the actuators 216. The righthand ends of the sleeves 424 and the shaft 423 have secured thereon gears (not shown) adapted to position a plurality of type carriers (not shown) according to the differential movement of the actuators 216.

Total-taking operations

This machine is also capable of performing total-taking operations. The total control lever 162 (Fig. 1) has four positions, namely, "add", "read", "reset" and "non-add". When it is desired to read the total on a totalizer the lever is moved to the "read" position and the machine operated in the usual manner. However, if it is desired to read the totalizer and reset it to zero, the total lever is moved to the "reset" position and an operation of the machine prints the total and resets the totalizer to zero.

Reading or sub-total operations

In "read" operations the totalizer is rocked into engagement with the actuators 216 at the beginning of machine operations. Then when the Universal rod 221 (Fig. 2) is moved forwardly the totalizer pinions 230 are rotated in a backward or counterclockwise direction until the long tooth 302 on each pinion is stopped by the forward end of the associated transfer trip pawl 300. This is the zero position of the totalizer pinions and the amount standing on the totalizer wheels will have been transferred to the actuators 216. Return movement of the rod 221 causes the amount to again be added upon the totalizer wheels and the indicator and type carriers adjusted accordingly.

The cam for controlling the engagement and disengagement of the totalizer during "read" operations is shown in Fig. 5. In order to make this controlling cam effective it is necessary to engage the stud 265 (Fig. 3) with a notch 725 (Fig. 5) of an arm 726 loosely mounted on the shaft 210.

As the total lever 162 (Fig. 3) is moved to the "read" position the stud 727 cooperating with the cam slot 728 rocks the arm 729, causing the stud 265 in the link 264 to engage the notch 725 in the arm 726.

The arm 726 (Fig. 5) is provided with a roller 732 which engages a cam race 733 in the lefthand side of the cam 452 mounted on the main cam shaft 89. The cam race 733 is so timed as to engage the totalizer with the actuators before the actuators move, and to disengage the totalizer after the Universal rod 221 is returned to its normal position, thus causing the amount to again be added on the totalizer, and the indicators and type carriers set up.

During totalizing operations the zero stop pawls 62 (Fig. 2) are rocked to ineffective positions in

the following manner. A stud 745 (Figs. 3 and 8) in the total lever 162 is adapted to cooperate with a camming surface on the lower end of an arm 746 secured to the shaft 533 when the total lever 162 is moved to the "read" or "reset" position to rock the arm 746 and shaft 533 counterclockwise. The counterclockwise movement of the shaft 533 causes an arm 534 (Fig. 2) secured thereon to also rock counterclockwise, causing a stud 535 in the arm 534 to engage the zero stop pawls 62 to rock them to ineffective positions during "read" and "reset" operations.

Reset or totalizing operations

A reset operation is performed in the same manner as a read operation, the only difference being that the totalizer is disengaged from the actuators 216 before said actuators are returned to their home positions. This prevents the amount from being re-entered in the totalizer.

Movement of the total lever 162 (Fig. 1) to the "reset" position, through the stud 727 cam slot 728 and arm 729 (Fig. 3) causes the stud 265 to engage the bifurcated arm 449. The arm 449 is rocked by the cam race 451 in the cam 452 as before described, and the timing thereof is such that at the beginning of the machine operation the totalizer is engaged with the actuators and after being returned to zero is disengaged therefrom before the Universal rod 221 is restored to its home position. Thus it is seen that with the totalizer disengaged when the actuators 216 are restored to normal, the amount will not be re-entered in the totalizer and therefore the totalizer will be left at zero.

Repeat release key mechanism

The repeat mechanism provided in this machine is characterized by the fact that the operator need not know at the time of making the original entry that the amount is to be repeated. Therefore an amount of a preceding transaction may be repeated at any time after said transaction. It is also possible to repeat a total operation after the totalizer from which said total was taken has been returned to zero. It is also possible by using the repeat release key to transfer a total from one totalizer to any other totalizer after the totalizer from which the total was originally taken has been returned to zero, or if desired, the total may be re-entered in the totalizer from which it was taken.

In repeat mechanism heretofore known in the art, it is necessary to make a preliminary setting before the original amount is entered in order that this amount may later be repeated. Such preliminary setting has been entirely done away with in the present invention. All that the operator need do is to glance at the indicators and if they show the amount which he desires to enter in the machine, he first sees that the total lever is in the "add" or "non-add" position and then presses the repeat release key which releases the machine to enter the desired amount. It is obviously a fact that a repeat mechanism such as this is useful in a great many lines of business and it is not desired to limit its use to any particular system or systems.

It will be recalled that the segments 421 at the end of machine operations (Fig. 2) are left standing in the positions to which they were adjusted under control of the depressed amount keys 58 in add and non-add operations and under control of the long teeth on the totalizer pinions 230 in read and reset operations. It will

also be remembered that the actuators 216 are always restored to their home or zero position. During repeat operations the segments 421 and the gears 422 and 425 together with the rod 430 are used for controlling the positioning of the actuators 216. As it is impossible to perform a repeat operation with any of the amount keys 50 depressed, other means must be provided for positioning the actuators 216. This means consists of the rod 430 which stops the gears 425 and through the gears 422 stops the segments 421 in their zero positions as above described.

Depression of the repeat release key 164 (Fig. 7) disconnects the link 446 from the stud 445 and therefore when the machine starts to operate the coupling pinions 440 will not be disengaged from the actuators 216 and the segments 421. A slot 401 cut in the lower end of the repeat release key 164 embraces the stud 445, thereby holding the arm 444 and pinions 449 in positive alignment when the repeat release key is depressed. Thus when the rod 221 (Fig. 2) receives its forward movement to restore the segments 421 to their zero positions the actuators 216 are moved like distances thereby setting up the actuators to the amount previously standing on the segments 421. During the return movement of the rod 221 the coupling pinions remain engaged with the actuators and segments and therefore the actuators 216 are returned to their home positions and the segments 421 are returned to the positions in which they were standing at the beginning of the repeat operation.

Repeat operations may be made only when the total lever is in either the "add" or as shown in Fig. 1, in the "non-add" position. With the total lever in the "add" position the amount previously standing on the segments 421 is again added into the pinions on the selected totalizer, and the indicators and type carriers are adjusted in the same manner as before described for adding operations.

The means for disconnecting the link 446 (Fig. 7) from the stud 445 consists of a slot in the repeat release key 164 through which the stud 447 projects. Depression of the repeat release key rocks the link 446 clockwise until it is disengaged from the stud 445.

It is not necessary to depress the motor bar 76 (Fig. 1) to release the machine for a repeat operation. Depression of the repeat release key 164 (Fig. 7) causes a stud 510 to enter a slot 511 in an arm 522 secured to the shaft 513 to rock said shaft counterclockwise. Counterclockwise movement of the shaft 513 (Fig. 3) causes a stud 515 in an arm 514 secured on the shaft 513 to engage the lower end of the release pawl 114 to withdraw said pawl 114 from beneath the flange 113 on the link 110 to release the machine for operation in exactly the same manner as described hereinbefore.

A spring 516 (Fig. 7) is arranged so that regardless of which direction the arm 512 and shaft 513 are rocked said spring will return and retain them in normal positions. A spring 519 (Fig. 7) is provided for retaining the repeat release key 164 in its normal ineffective position against the stop stud 520 in the frame 54. The frame 54 also carries a stud 521 for limiting the downward movement of the repeat release key.

As the actuators 216 are moved under control of the segments 421 during repeat operations, it is necessary that the zero stop pawls 62 (Fig. 2) be rocked to ineffective positions and this is accomplished in the following manner: The repeat

release key 164 carries a stud 530 (Fig. 7) which when the repeat release key is depressed enters a slot 531 in an arm 522 secured to the shaft 533 to rock said shaft counterclockwise. This causes the stud 535 (Figs. 2 and 8) in the arms 534 to engage the zero stop pawls 62 and rock them to ineffective positions during repeat operations. The arm 534 is also provided with a flange 536 which is rocked into the path of a pawl 537 pivoted on the flexible detent 57. Thus when the arm 534 is rocked counterclockwise by the depression of the repeat release key the flexible detent 57 is locked against movement, which in turn locks the amount keys 50 against depression during repeat operations.

As previously set out the amount keys are released by rocking the flexible detent 57 downward, and as this detent is locked against movement during repeat operations, it is necessary that the automatic releasing mechanism for the amount keys be disabled during repeat operations. While this releasing and release disabling mechanism is not here shown, reference may be had to the parent application for a full description thereof.

Repeat release key lockout mechanism

Means is also provided for preventing operations of the repeat release key if any one of the keys in any of the amount banks has been depressed. The depression of an amount key rocks its respective flexible detent 57 (Fig. 2) downwardly, thereby positioning the pawl 537 on said detent in the path of the flange 536 on the arm 534, thus blocking the counterclockwise movement of the shaft 533 and thereby preventing depression of the repeat release key 164.

As previously stated, the yoke 157 (Fig. 7) is provided with an upwardly extending arm 163 for preventing depression of the repeat release key after the machine has been released for operation. The arm 163 is provided with a surface 542 which is rocked beneath the stud 530 on the repeat release key when the machine is released for operation by the motor bar 76, thereby locking the repeat release key 164 against depression.

The arm 163 has a recess 543 (Fig. 7) which passes over the stud 530 when the repeat release key is fully depressed, thereby permitting clockwise movement of the yoke 157 which allows the machine to release.

Interlocks

When the total lever 162 (Fig. 3) is moved to "read" or "reset" position a stud 745 (Fig. 3) fast therein engages an arm 746 secured to the shaft 533, to rock said shaft counterclockwise thereby moving the flange 536 (Fig. 2) on the arm 534 beneath the pawl 537 on the flexible detent 57. This locks all keys, except the transaction keys, against depression during totalizing operations. This same train of mechanism likewise prevents moving the total lever to the read or reset position when any of the amount keys 50 are depressed, as this rocks the pawl 537 into the path of the flange 536 thereby preventing counterclockwise movement of the shaft 533.

Movement of the total lever 162 (Fig. 3) to either "read" or "reset" position also locks out the repeat release key 164 in the following manner. The total lever is provided with a cam surface 780 which engages a stud 781 in the arm 514 when the total lever is moved to "read" or "reset" position. This movement of the arm 514 rocks the shaft 513 and the arm 512 clockwise 75

thereby positioning the locking surface 522 (Figs. 7 and 8) beneath the stud 510 on the repeat release key to prevent depression thereof.

Means are also provided for locking the ma-

chine against release when the total lever 162 is not properly adjusted in one of its four positions. Such locking mechanism, while not here shown, is fully illustrated and described in the parent application.

10 *Transfer totals*

Totals may be transferred from one totalizer to another any time after a read or reset total-taking operation is completed. No preliminary setting is necessary. Thus the totals can be transferred even though the operator does not know at the time of making the read or total-taking operation that such total is to be transferred.

The transferring of a total is effected by the repeat release key 164. In transferring a total from one totalizer to another all the operator need do is to make a total or sub-total operation, then position the selecting lever 319 (Fig. 10) to select another totalizer and depress the repeat release key whereupon such total or sub-total, as the case may be, is transferred into the selected totalizer.

During any total-taking operation the segments 421 are adjusted to represent the amount standing on the totalizer. Upon subsequent depression of the repeat release key the actuators 216 are controlled in the same manner as described for repeat operations and therefore it can be seen that the amount taken from the totalizer will be added into the subsequently selected totalizer.

If after a reset operation it is desired to reenter the total on the totalizer, this may be done by the repeat mechanism. At the end of a reset operation, the amount taken from the totalizer remains in the segment 421 and therefore in order to reenter this amount all that is necessary is to move the total lever to the add position and press the repeat release key. During this operation the segments 421 (Fig. 2) control the differential positioning of the actuators 216 in the same manner as previously described for adding repeat operations.

In view of the foregoing description it is felt that a statement of the operation and use of the machine is unnecessary. However, a brief summary will be given of the functions of the machine.

The machine of the instant invention is provided with two totalizers, either of which may be selected for adding, reading or resetting by means of the totalizer selecting lever 319 and the total lever 162. The totals standing on the totalizers may be read and re-entered in the totalizers, or the totals may be read and the totalizers reset to zero. This is controlled by the total lever 162 which has four positions of adjustment, namely, "non-add", "add", "read" and "reset". When the total lever is in the "non-add" position the depressed amount keys 50 serve only to position the indicators and the type carriers. When the repeat release key is used with the total lever in "non-add" position the indication and printing of the amount of the preceding transaction is duplicated.

A total may be taken from either totalizer and transferred to the other. This operation consists of taking a total in the ordinary way selecting the desired totalizer and then depressing the repeat release key. This mechanism is also use-

ful when the operator makes a reset operation by mistake, as he may re-enter the amount on the cleared totalizer by depressing the repeat release key.

While the forms of mechanisms herein shown and described are admirably adapted to fulfill the objects primarily stated, it is to be understood that it is not intended to confine the invention to the forms of embodiment herein disclosed, for it is susceptible of embodiment in various forms all coming within the scope of the claims which follow.

What is claimed is:

1. In a machine of the class described, the combination of a plurality of totalizers; a single manipulative device for directly selecting the totalizers for operation; means to condition the machine for taking totals from a selected totalizer; devices differentially settable under control of the selected totalizer when a total is taken from said selected totalizer; elements automatically settable under control of the devices during every total taking operation of the machine; and means operable subsequently to any total-taking operation to condition the machine whereby said elements control said devices to add the total taken during the previous operation into any one of the selected totalizers.

2. In a machine of the class described, the combination of a plurality of totalizers; means to condition the machine for taking totals; devices operable during a total taking operation to take a total from any totalizer; elements automatically settable during every total taking operation of the machine under control of the devices; a single manipulative device operable prior to a machine operation for directly selecting another totalizer; and a manipulative member, operable after any total-taking operation and after the selection of another totalizer, to condition the machine whereby the elements control the devices for adding the amount taken from the totalizer during the next previous operation into the second mentioned selected totalizer.

3. In a machine of the class described, the combination of a plurality of totalizers; totalizer selecting mechanism operable to completely select a totalizer prior to a machine operation; manipulative means to condition the machine for taking totals; means operable during a total-taking operation to take a total from a totalizer; elements automatically settable commensurate with the total taken during every total-taking operation of the machine; and a manipulative device to condition the machine to control the operation of the element whereby the element controls the extent of movement of the second named means for causing the total taken from the first selected totalizer to be added into a subsequently selected totalizer, said manipulative device adjustable after the operation during which the total is taken from the first totalizer.

4. In a machine of the class described, the combination of a plurality of totalizers; actuators therefor; totalizer selecting mechanism manually operable to completely select a totalizer prior to a machine operation; means for controlling the actuators for taking a total from any totalizer; a potentially effective mechanism automatically settable during every total-taking operation; and a manipulative member, operable subsequently to any operation of the machine during which a total was taken, to control the settable mechanism in such a manner that the

settable mechanism controls the actuators for adding the total into another totalizer.

5. In a machine of the class described, the combination of a plurality of totalizers; manually operable totalizer selecting mechanism to directly select a totalizer; amount determining devices; totalizer actuators, differentially adjustable under control of the amount determining devices, to add amounts into a selected totalizer; means for taking a total from any totalizer; a mechanism automatically settable during every total-taking operation to represent the total taken from the totalizer; and a manipulative member operable subsequently to any total-taking operation to control said mechanism to cause said mechanism to control the actuators to add the amount taken from the totalizer into another totalizer.

6. In a machine of the class described, the combination of a plurality of totalizers; a shiftable support for the totalizers; totalizer selecting mechanism comprising a manually operable lever and connections directly therefrom to the totalizer support to shift the support directly by operation of the lever; amount or data determining devices; actuators controlled by said devices to add into the totalizers; means for controlling the actuators for taking the total from any totalizer; a normally effective mechanism automatically settable under control of the actuators during every total-taking operation; and a manipulative member operable subsequently to any total-taking operation for controlling said mechanism and the actuators for transferring the amount taken from the totalizer into another totalizer.

7. In a machine of the class described, the combination of a plurality of interspersed totalizers mounted on a common support; totalizer selecting mechanism comprising a manipulative device and connections to directly shift the support; actuators for the totalizers; means to control the actuators to take a total from any one of said totalizers; means set under control of the actuators during total-taking operations; and a manipulative means operable after any total-taking operation to control the last-named means for determining the extent of movement of the actuators to effect the registration of the total taken from the totalizer directly upon any totalizer on the same support.

8. In a machine of the class described, the combination of a plurality of interspersed totalizers mounted on a common support; totalizer selecting mechanism comprising means to shift the support prior to a machine operation; actuators for the totalizers; means to control the actuators for taking totals from any of said totalizers; storage elements set simultaneously with the setting of the actuators for storing the total taken from the selected totalizer; and a manipulative device adapted to control the storage elements whereby the storage elements control the extent of movement of the actuators for causing the amount of the total taken to be accumulated directly upon a subsequently selected totalizer on the common support, said manipulative device being inoperative during the operation wherein a total is taken.

WILLIAM H. ROBERTSON.
